UNITED STATES PATENT OFFICE.

JEREMIAH VANDERBILT, OF BROOKLYN, NEW YORK, ASSIGNOR TO ROBERT LEFFERTS, OF SAME PLACE.

DESIGN FOR A CANDLE-SHADE.

SPECIFICATION forming part of Design No. 26,786, dated March 23, 1897.

Application filed February 4, 1897. Serial No. 622,050. Term of patent 7 years.

To all whom it may concern:

Be it known that I, JEREMIAH VANDERBILT, a citizen of the United States, residing at Brooklyn, county of Kings, and State of New York, have invented and produced a new and original Design for Candle-Shades and the Like, (Case A,) of which the following is a specification.

My invention relates to a design for a candle or lamp shade; and it consists in the configuration and disposition of parts, substantially as illustrated in the accompanying drawings, forming part of this specification, in which—

Figure 1 is a plan view; Fig. 2, a side elevation, and Fig. 3 a sectional elevation.

The design consists of a series of petal-like pieces configured to form substantially a truncated cone-like figure in side elevation and a circular figure with concentric rings, in plan, the cone being surmounted by a sheaf-like disposition of the petal-like pieces.

The cone-like base 1 of the shade, which has a crimped surface, is provided with a thick and annular base-piece 2. At the top of base 1 is a conical ring 3, surmounted by an annular ring 4.

The foregoing serves as a support and outline, giving body for the disposition of the petal-like pieces.

30 The lower range of petals 5, each petal

consisting of a piece of fabric or the like of a suitable figure folded over on itself, as at 6, centrally, are secured at their upper ends to the exterior of the base 1, as at 7, the ends extending below the base-piece 2, the fold 6 of the petals overlapping their edges 8, as shown in Fig. 2.

The upper petals 9, formed and disposed in the same way as the petals 5, are secured to the rings 3 4, their edges 8 extending reversely to those of the petals 5, their lower portions 10 lying in the same plane, their upper portions 11 extending upwardly from the ring 4, which gives the petals the sheaf-like effect, this contraction being emphasized by a band 12, of ornamented braid or the like, secured on the petals and pressing them against the ring 4.

The petals are provided with line-like surface ornamentation.

Having described my invention, I claim—

The design for candle-shades, or the like, substantially as herein shown and described.

Signed at the city, county, and State of New York, this 30th day of January, 1897.

JEREMIAH VANDERBILT.
